UNITED STATES PATENT OFFICE.

ALBERT E. MCGILL, OF CHICAGO, ILLINOIS, ASSIGNOR TO ALWIN MFG. CO., OF CHICAGO, ILLINOIS, A CORPORATION OF ILLINOIS.

PERAMBULATOR.

No. 800,471.

Specification of Letters Patent.

Patented Sept. 26, 1905.

Application filed October 15, 1902. Serial No. 127,359.

To all whom it may concern:

Be it known that I, ALBERT E. MCGILL, a citizen of the United States, residing at Chicago, in the county of Cook and State of Illinois, have invented certain new and useful Improvements in Perambulators, of which the following is a full, clear, and exact specification.

My invention relates more particularly to 10 that class of perambulators or go-carts intended for small children; and it has for its primary object to provide an improved and durable construction of perambulator or go-cart which shall be capable of folding into a 15 compact form.

With these ends in view my invention consists in certain features of novelty in the construction, combination, and arrangement of parts by which the said objects and certain 20 other objects hereinafter appearing are attained, all as fully described with reference to the accompanying drawings, and more particularly pointed out in the claims.

In the said drawings, Figure 1 is a plan 25 view of my improved perambulator or go-cart. Fig. 2 is a side elevation thereof. Fig. 3 is an enlarged detail sectional view taken on the line 3 3, Fig. 1. Fig. 4 is a front elevation of the complete device. Fig. 5 is a detail longitudinal sectional view taken on the line 5 5, Fig. 1. Fig. 6 is a side elevation of 30 the device folded up or nearly folded up. Fig. 7 is an enlarged plan view of a portion of one of the side members and the joint of 35 the handle; and Fig. 8 is an enlarged cross-section on the line 8 8, Fig. 2.

The wheels 1, preferably four in number, are journaled in any suitable supports, brackets, or braces—such, for example, as forks 2. 40 The manner of attaching these forks to the frame of the vehicle is the same for each, and therefore the description of one will suffice for all. The fork is formed on or secured to a collar 3, and these collars are sleeved on side 45 bars or members 4, which constitute the sides of the frame or part which might be called the “running-gear” frame, so that the collars will be capable of a limited degree of rotary motion, and consequently when desired the 50 forks may be folded under the vehicle toward each other in the manner illustrated in Fig. 6, thus lapping the wheels on one side over the wheels on the other side. In order, however, that the forks may not rotate too far

when being turned downwardly to their operative position, as shown in Fig. 4, the collars are provided with shoulders 5, which when the forks are at an upright position ready for use, as shown in Fig. 4, engage with shoulders 6, formed on four fittings 7, 60 secured to the ends of the side members 4, and also constituting means whereby cross members 8 9 of the running-gear are attached to the side members 4 and by which a rectangular running-gear frame is constituted 65 with one of the wheel-forks rotatively mounted at each corner thereof.

In order that the front and rear forks, brackets, or braces for the wheels may be connected together in pairs, so that the rotary 70 movement of one on each side will be imparted to the other on the same side, they are rigidly secured to side bars 4^a, journaled on the side members or bars 4, the bars 4^a being preferably composed of two telescoped 75 tubes, as clearly shown in Figs. 5 and 8.

The collars 3 are rigidly secured to the outer tube 4^a in any suitable way, as by brazing or otherwise, and this tube turns freely upon the inner tube 4 between the two end fittings 7 80 as far as the shoulders 5 6 will permit. When the wheels arrive at an upright position ready for use, as shown in Fig. 4, the outer tube 4^a may be held against rotation on the inner tube by any suitable pin or lock, preferably passing through the tubes. As a means of accomplishing this, I prefer to employ a brace 10, which is in the form of a rod with its lower end passing transversely through the tubes 4^a and having a bend or shoulder 11, which limits its downward movement, while the upper end of this brace is bent at an angle, as shown at 12, and engages in the side of a pivoted seat-support composed, preferably, of a U-shaped member 13, one of the braces 10 being 95 of course employed on each side, and thus serving the twofold purpose of locking the wheel-forks against rotary motion and supporting the seat-support 13 at the desired elevation above the running-gear members 4 8 9. 100

The U-shaped seat-support 13 is preferably composed of a piece of bent tubing for the sake of strength and lightness, and the lower ends of its branches are pivoted in any suitable way to the running-gear, preferably by 105 means of collars 14, journaled on the cross member 9 between the fittings 7 at one end of the running-gear, so as to be capable of being

folded up between the side members 4 of the running-gear and substantially in a plane therewith. The seat-support 13 may be thus lowered until its upper end rests upon the cross member 8, when the braces 10 are removed, their upper angular ends 12 being fastened in suitable sockets in sides of the seat-support, and the removal of these braces also permits the wheel-forks to be folded under the running-gear frame, as before described. In order that the lower edge of one wheel may fold up a little higher than the other wheel, the cross members 8 9 are bent upwardly at their mid-lengths, as shown at 8^a and 9^a, respectively, without, however, interfering with the full downward movement of the seat-supporting member 13, whose sides embrace the upwardly-bent portion 8^a of the cross member 8.

15 is the seat, which while in use may be supported in substantially a horizontal position by means of a pivoted cross-bar 16, whose ends are journaled in the sides of the seat-support 13 and which cross-bar pivotally supports the forward edge of the seat, while the rear edge is supported by any suitable flexible connection—such, for example, as one or more cords 17, having their lower ends attached to the seat, while their upper ends are passed through perforations 18 in the cross member 30 of the seat-support and then knotted to prevent them from pulling through, as shown at 19.

20 is a foot-rest whose forward edge is secured by pin 21 to the cross member 9, while its rear edge is supported by a flexible connection or cord 22, preferably a single cord, which passes through the cross-bar 16, which is hollow for that purpose.

23 is a handle by means of which the device 40 may be pushed or pulled and which handle preferably consists of a U-shaped bar having its branches pivotally secured to the running-gear, so as to be capable of folding down over the latter, as shown in Fig. 6. This figure of 45 the drawings, however, does not show the handle 23 folded down as far as possible, excepting in dotted lines, it being left a little elevated for the purpose of illustrating the parts beyond, and when so folded down its side members embrace the upwardly-bent section 9^a of the cross member 9—that is to say, said upwardly-bent section when the handle is folded down stands in a plane substantially the same as the plane of the handle. In order that the 55 handle may be thus pivoted to the running-gear and folded over it, the pivotal points between the handle and the running-gear are slightly elevated relatively to the running-gear, as better illustrated in Fig. 5, in which 60 it appears that the rear ends of the inner tubes 4 are provided with plugs 24, whose outer ends are turned upwardly and formed with hinge members 25, which match hinge members 26, formed on the lower ends of the handle and which are pivoted thereto by set-

screws 27. The contiguous faces of the hinge members 25 26 are provided with teeth or serrations 28, so that the handle may be locked in the desired position.

In Fig. 2 of the drawings the seat-support 70 13 and seat 15 are shown at an inclination suitable for a sitting or slightly-reclining posture; but it will nevertheless be understood that the inclination of the seat-support 13 may be varied at will by changing the position of the 75 braces 10, for the accomplishment of which the sides of the seat-support 13 are provided with additional holes or sockets 29 for the reception of the upper angular ends 12 of the braces and the tubes 4 4^a with additional perforations or sockets 30 for the reception of the lower ends of said braces.

Having thus described my invention, what I claim as new therein, and desire to secure by Letters Patent, is—

1. In the device for the purpose described the combination with running-gear frame comprising side members, of outer members or bars sleeved rotatably on said side members, wheel-supports secured in pairs to said outer 90 members respectively, and said pairs being adapted to fold toward each other transversely of the running-gear frame, and means for holding said wheel-supports in their operative positions.

2. In a device for the purpose described the combination of a running-gear frame having side members, outer members sleeved rotatably upon said side members, said side and outer members having transverse perforations, 100 wheel-supports secured to said outer members and adapted to fold up transversely of the running-gear frame, a seat-support pivoted with relation to the running-gear frame and braces for supporting said seat-support, adapted to enter said transverse perforations for locking said side and outer members against relative movement, substantially as set forth.

3. In a device for the purpose described the combination of a running-gear frame having 110 horizontal side members, a seat-support pivoted at its forward end between and flush with the forward ends of said side members, said seat-support being of less width than the running-gear frame so as to lie flush between said side members in a plane therewith, means at the rear end of said seat-support for supporting the same on said side members at an angle thereto, wheels, wheel-supports pivoted on axes extending through said side members 115 and adapted to fold up transversely thereof across said seat-support, and means for locking said wheel-supports against pivotal movement.

4. In a device for the purpose described, the combination of a running-gear frame having straight longitudinal side members, a tube sleeved on each of said members, wheel-supports rigidly secured to the four ends of said tubes, means for locking said tubes against 120

130

rotary movement on said side members, a seat-support pivotally supported upon and adapted to fold up with said side members, and a handle secured to said running-gear frame and 5 adapted to fold up with said seat-support.

5. In a device for the purpose described, the combination of a running-gear frame having straight longitudinal side members, a shoulder at each end of each of said side members, a tube sleeved on each of said side members between said shoulders, shoulders carried by said tubes at each end of each thereof and adapted to engage with said first shoulders respectively when the tubes are rotated throughout a certain degree, four wheel-supports rigidly secured to the four ends of said tubes respectively and adapted to fold transversely across the running-gear frame when said tubes are rotated, a seat-support pivotally supported 10 on said running-gear frame and adapted to fold up therewith, and a handle pivotally secured to the running-gear frame.

6. In a device for the purpose described, the combination of a running-gear frame comprising straight longitudinal side members, elevated hinge members attached to the rear ends of said side members respectively, a straight U-shaped handle having its extremities hinged to said hinge members respectively, and being of the same width so as to fold down parallel with and against said side members, a U-shaped seat-support having its extremities pivotally secured to the end of the running-gear frame opposite the end thereof 15 carrying said hinge members, said seat-support being of less width than said handle, and

wheel-supports pivoted on axes extending longitudinally of the running-gear frame and adapted to fold thereacross.

7. In a collapsible carriage, the combination of the wheels, axles for said wheels, a frame, rotatable side bars, and brackets whereby the wheels are carried by the side bars.

8. In a collapsible carriage, the combination of a frame, bearings carried by said frame, 45 side bars rotatable on said bearings and a plurality of wheels carried by each side bar.

9. In a perambulator, the combination of a running-gear frame, two tubes sleeved on the side members thereof, respectively, wheel-forks secured to said tubes and rotatable therewith, said tubes and running-gear frame having registering sockets, or perforations, a seat-frame hinged to said running-gear frame, a seat-frame support hinged to said seat-frame 50 and adapted to fold up therewith, and pins on said support for engaging in said perforations when the seat-frame support is in an upright position.

10. In a perambulator, the combination of a running-gear frame, a seat-frame hinged at one end to said running-gear frame and being narrower than the latter, and a U-shaped handle hinged to the other end of said running-gear frame and being wider and longer 65 than said seat-frame and adapted to fold down against the running-gear frame, so as to embrace the seat-frame.
